US0D1042014S

(12) **United States Design Patent** (10) Patent No.: **US D1,042,014 S**
(45) Date of Patent: ** Sep. 17, 2024

(54) **BEVERAGE ADDITIVE CARTRIDGE CAP**

(71) Applicant: **Cirkul, Inc.**, Tampa, FL (US)

(72) Inventors: **Garrett S. Waggoner**, Tampa, FL (US);
Andrew Gay, Bothell, WA (US); **Cole Houston**, Central Falls, RI (US);
Thomas A. Urbanik, Maynard, MA (US)

(73) Assignee: **Cirkul, Inc.**, Tampa, FL (US)

(**) Term: **15 Years**

(21) Appl. No.: **29/846,655**

(22) Filed: **Jul. 18, 2022**

CLAIM

The ornamental design for a beverage additive cartridge cap, as shown and described.

DESCRIPTION

FIG. 1 is a perspective view of a beverage additive cartridge cap showing our new design;

FIG. 2 is a bottom perspective view of the beverage additive cartridge cap of FIG. 1;

FIG. 3 is a front view of the beverage additive cartridge cap of FIG. 1;

FIG. 4 is a rear view of the beverage additive cartridge cap of FIG. 1;

FIG. 5 is a left side view of the beverage additive cartridge cap of FIG. 1;

FIG. 6 is a right side view of the beverage additive cartridge cap of FIG. 1;

FIG. 7 is a top view of the beverage additive cartridge cap of FIG. 1; and,

FIG. 8 is a bottom view of the beverage additive cartridge cap of FIG. 1.

The features shown in broken lines are included to show portions of the beverage additive cartridge cap that form no part of the claimed design.

1 Claim, 4 Drawing Sheets

Related U.S. Application Data

continuation of application No. 29/695,668, filed on Jun. 20, 2019, now Pat. No. Des. 912,462, which is a continuation-in-part of application No. 29/624,862, filed on Nov. 3, 2017, now Pat. No. Des. 872,520.
